We claim the ornamental design for a mobile terminal, as shown and described.

DESCRIPTION

FIG. 1 is a top front perspective view of a mobile terminal showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another right-side view, in which the mobile terminal is provided in an open position;

FIG. 9 is another top front perspective view, in which the mobile terminal is provided in an open position;

FIG. 10 is a bottom perspective view, in which the mobile terminal is provided in an open position; and,

FIG. 11 is another perspective view thereof, in which the mobile terminal is provided in a partially open position.

The broken lines in the figures show portions of the mobile terminal which form no part of the claimed design.
